(57) **CLAIM**

The ornamental design for a cooler, as shown and described.

DESCRIPTION

FIG. 1 is a front view of a cooler showing the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top front perspective view of the cooler of the present invention showing the claimed design in an environment in which it may be used.

The broken lines in the figures show portions of the cooler and environment that form no part of the claimed design.

1 Claim, 6 Drawing Sheets
